UNITED STATES PATENT OFFICE.

PAUL H. TAYLOR, OF WAKEFIELD, MASSACHUSETTS.

PIANO.

Application filed February 28, 1927. Serial No. 171,425.

This invention relates to piano actions and aims to provide a novel and improved construction, one object of which is to provide a constantly increasing velocity and therefore 5 greater force of impact for the hammer against the key while the key is depressed at a uniform speed, and having, among others, the novel features and advantages herein-after described.

10 In the drawing of one embodiment of my invention selected for description and illustration herein,

Fig. 1 is a side elevation of my novel action; 15 Fig. 2, a detail, enlarged, of portions of the key and wippen showing the contacting point between the two when the key is depressed half way; and

Fig. 3, a similar view of the same parts 20 when the key is depressed to its full extent.

In the drawing, Fig. 1, the key 1 is shown fulcrumed by any suitable construction, as the washer 2, pin 3 and V-shaped slot 4, dotted lines, upon the support 5. The key 25 is provided at a suitable point with a novel upstanding wippen actuating post 6 having a curvilinear top constructed to cooperate with the suitably fashioned end of a downwardly extended post 7 on the lever 8 of the 30 wippen, the latter being provided also with the jack 9, hammer 10 as well as other conventional parts not pertinent hereto.

While the cooperating surfaces of the key and wippen may be so shaped as to 35 give any desired proportionate acceleration to the hammer 10 as compared to the action of the key 1, I prefer a logarithmically accelerated action of the hammer, and have shown a construction designed to effect it, 40 because such proportionate action is in accord with the law of response or receptivity of the ear to the intensity of sound. In other respects the construction of the wippen may be along conventional lines.

45 When the key 1 is struck, Fig. 1, the contact between the posts 6 and 7 is first made substantially at the point 11 on the post 6, and as the key is further depressed a succession of points of contact follow, and the 50 contact point is advanced until, Fig. 1, when the key is depressed to the point designated *d*, in the diagram of its line of travel, and the hammer is raised to the point marked *d*, in the diagram of its path of travel, the

contact point, between the two elements, Fig. 55 2, is substantially at the point marked 12.

When, Fig. 1, the hammer is depressed to the limit, point *e* in its line of travel and the hammer is raised to its highest point *e*, the 60 point of contact, Fig. 3, of the two posts 6, 7, is advanced substantially to the point 13.

It will be noted that, in the present case, every point of contact between the posts 6, 7, will be made on the straight line *z*—*z* between the fulcrum of the key and fulcrum of 65 the wippen action. Heretofore the contacting surfaces of the usual capstan screw on the key and the wippen, or their equivalents, and the action of the key and wippen have not been designed to provide a succession of 70 contacting points, but instead a progression of contacting and sliding surface areas with the result that there has always been substantial friction between the two surfaces which, by my novel construction, is materially 75 eliminated; and there has been a lack of definitely predetermined accelerated rate of speed between the key and hammer of the action, with the result that the hammer speed has not been variable with respect to the 80 key speed and the hammer blows have been indefinitely uneven as to intensity measured by tone sensation.

By the foregoing described construction a constantly and regularly accelerating 85 velocity of travel of the hammer is obtained so long as the hammer button rests upon the jack, according to the nature of the blow upon the key by a uniform velocity of the key, which is much easier and less tiring for 90 the meticulous player. Furthermore, the pressure of the finger on the key is caused to be transmitted through the action and then to maintain the driving power upon the hammer button throughout the entire length 95 of the travel of the jack. The velocity of the hammer travel does not become great enough from the initial movement of the key to cause it to run away from the jack as has hitherto been the case.

100 One result of this mode of operation is that the force of the impact of the hammer against the string is more uniform throughout a series of notes than when the hammer runs away from the jack; and this with the 105 definitely accelerated rate of speed of the hammer results in more uniformity of playing with respect to loudness, or intensity and

markedly better tone volume control by the player. Furthermore, the conscious effort of the meticulous player need not be focused so much upon his finger pressure upon the 5 key, as is now necessary.

It will be noted, Fig. 1, that the key measurement from the fulcrum point on the pin 3 to the point 11 on the post 6 is less than from the fulcrum to the point 13, but 10 the key co-operates with the lever 8 of the wippen, the measurement of which from the fulcrum or pivot point 14 of the lever 8 to the point 13 is less than from the point 14 to the point 11.

15 This change of ratios in the effective key and wippen measurements is also effected as to any point between 11 and 13 in accordance with any selected law, as for instance the logarithmic, in this case.

20 The contact between the posts 6, 7, is more of a rolling or gear tooth contact than of a sliding one as in the present form of construction of the key and wippen.

25 My novel action enables a pianist with greater certainty to cause the hammer to strike the strings very lightly for pianissimo and very heavily for fortissimo so that, in the latter case, the volume of sound will be increased to such an extent and in such a 30 way that the effect upon the ear will be more nearly in accordance with the law of the logarithmic response of the ear to the intensity of the sound.

For example, if in order to produce three 35 times the loudness of sound in fortissimo it would theoretically require that the hammer possess nine times the energy, which is the result of speed, at the moment of impact, then this we would attain by greatly increasing the velocity, as explained, which 40 increase of velocity is obtained by more efficient and better controlled transmission of the speed of the finger on the key than heretofore, as explained above.

45 My invention is not limited to the embodiment thereof herein shown and described.

Claimis:

1. A piano action comprising a key, a 50 wippen with a hammer, curved contacting surfaces on the key and wippen, said members cooperatively mounted one relative to the other, and providing, on movement of the key, a continued rolling contact between them along a straight line.

2. A piano action comprising a key, a wippen with a hammer, curved contacting surfaces on the key and wippen, said members cooperatively mounted one relative to 60 the other, and having, on progressive travel of the key, contact at a succession of points on a curved surface between the curved sur-

faces at a continued accelerating speed of the hammer.

3. A piano action comprising a key, a 65 wippen with a hammer, cooperating contacting surfaces on the key and wippen, said members engagingly mounted relatively to each other and producing, on progressive travel of the key, contact on a curve at a 70 succession of points successively between the key and wippen surfaces, and also along a straight line between the key and wippen fulcrs producing continued accelerating speed of the hammer according to any selected law of acceleration. 75

4. A piano action comprising a key, a wippen, cooperating contacting surfaces on each, the measurement of the key from its fulcrum to the first point of contact of the key with the wippen being less than the measurement from the fulcrum of the key to any subsequent point of contact of said parts, while the measurement of the wippen from its fulcrum to its first point of contact with the key is greater than the measurement to any subsequent point of its contact with the key. 80

5. A piano action comprising a key, a wippen, curved contacting surfaces on each, the parts so assembled that the movement of the key produces a rolling contact between it and the wippen along curvilinear surfaces and an angularly directed straight path. 90

6. A piano action comprising a key, a wippen, contacting surfaces on each and engaging each other in action along a convex and a concave surface. 95

7. A piano action comprising a key, a wippen, contacting surfaces on each, the parts engaging each other when in action along a concave and a convex surface, every point of contact being on a straight line passing through the fulcrs of the key and wippen. 100

8. A piano action comprising a key, a wippen, contacting surfaces on each, the parts engaging each other when in action along a concave and a convex surface, every point of contact being in the plane of a straight line passing through the fulcrs of the key and wippen, and producing accelerated speed of the hammer according to an approximately logarithmic ratio. 110

9. A piano action comprising a key and wippen cooperatively mounted and provided with arcuate opposed faces, the first point of contact of which in action is on a straight line between the fulcrs of the key and the wippen. 115

In testimony whereof, I have signed my name to this specification.

PAUL H. TAYLOR.
